UNITED STATES PATENT OFFICE.

ARTHUR S. HAWKS, OF ST. LOUIS, MISSOURI, ASSIGNOR TO BUSCH-SULZER BROS.-DIESEL ENGINE COMPANY, OF ST. LOUIS, MISSOURI, A CORPORATION OF MISSOURI.

PUMP-VALVE MECHANISM.

Application filed September 30, 1918. Serial No. 256,295.

To all whom it may concern:

Be it known that I, ARTHUR S. HAWKS, citizen of the United States, residing in St. Louis, Missouri, have invented the following described Improvements in Pump-Valve Mechanisms.

The invention is a valve mechanism suitable for compressors and pumps, especially air pumps, and involving principles which afford a large capacity and other advantages hereinbelow made apparent to those skilled in this art.

In the accompanying drawings—

Fig. 1 is a longitudinal section through a pump cylinder having the invention applied;

Fig. 2 a section thereof on line II—II;

Fig. 3 is a perspective detail of the valve assemblage;

Fig. 4 an enlarged vertical section through the pivoted valve members, illustrating different positions; and taken on line IV—IV of Fig. 5;

Fig. 5 is a section on line V—V of Fig. 4; Fig. 6 illustrates in section a modified form of valve member; and

Figs. 7 and 8 are horizontal and vertical sections respectively of the valve mechanism of Fig. 4, provided with a terminal seat for the valve members.

In these figures a double acting pump or compressor cylinder is represented at 1 having a piston 2 and inlet and outlet ports 3 and 4, each equipped with valve mechanism according to this invention, and a delivery pipe or passage 5 receiving the discharge from the outlet ports. The valve mechanisms for the inlet and outlet ports are shown as reversely-acting duplicates and each comprises one or more rectangular, adjacent, valve frames 6 formed on or bolted to the wall of the cylinder structure in any appropriate way so as to control their respective port passages. There are four of such frames for each cylinder port in the case illustrated and all are fitted close together in a common plane but their disposition and number as well as their shape are matters of design to be varied according to circumstances.

Each valve frame contains or carries an organization of imbricated valve members each consisting of a louver 8 pivotally mounted in the frame and adapted to swing on its pivotal axis from the open position

shown at the bottom of Fig. 4 to the closed position shown at the top of the same figure. In the closed position each louver seats by its longitudinal free edge upon the pivoted side or edge of its next adjacent neighbor, thereby providing a series of multiple cooperating valve members. The lowest louver of the series seats on a fixed ledge 9 on the lower cross member of the valve frame. The valve frame as shown in Figs. 4 and 5 is comprised of integral top and bottom cross bars 10 and narrower side bars 11 and the gudgeon pivots 13 of the several louvers are mounted in a series of holes bored in two auxiliary side plates 12 which are bolted to opposite sides of the frame. The ends of the body part or blades of the louvers are dressed off square and with a very slight clearance from the flat faces of the plates, 12, in which they are pivoted so that the crevice between the ends of the louvers and the surfaces of said plates is sufficiently narrow to prevent undue leakage. By making the leak path through these narrow crevices still longer, as by using louvers with thicker blade portions, they become practically tight for all moderate pressures but other means for sealing the crevice may be also provided as presently described. The louvers may have various cross-sectional shapes; those shown in Figs. 4 and 5 having all of their blade portions on one side of their pivotal axes, are unbalanced to the pressure while those shown at 8^a in Fig. 6 have part of their blade surfaces disposed on each side of their axes and are therefore partly counterbalanced, that is to say, in Fig. 6 pressure of the fluid on the members when closed acts on each of them on opposite sides of the pivotal axis so that the pressure with which any valve member seats upon its neighbor is the difference of the pressure acting on opposite sides of its axis and the lower side of the member being of the larger area, this side seats upon the smaller side of the next lower member by the effect of such difference. The opening movement of the series of louvers is limited to less than 90° by a series of stops 14 formed in the edge of the guide bars 11 of the valve frame, one for each louver. Gravity returns the louvers and to assist this action the lines of holes bored in the side plates 12 are arranged at an inclination so that each louver may encounter its seat on the one next below before it reaches a verti-

cal position, thus tending to seat with some gravitational pressure irrespective of the fluid pressure that may be acting thereon.

The louvers can be readily made, each of a single piece as shown in the drawings and of any desired degree of rigidity according to its length and thickness. It is preferably thinner in its blade portion than in the region of its axis and its said axis is parallel with its longest dimension so that it has relatively little inertia and is correspondingly quiet in action. These valve members may be manufactured at low cost from bar stock which has been rolled, drawn or extruded to a flat section substantially like that shown in the drawings and having an enlarged bead along one side (in line with the pivotal axis). By cutting this stock in sections, the side beading can be readily utilized to form the pivot. The said members may also be die-cast as will be obvious.

For use at higher pressures or when the slight leakage through the crevices at the ends of the louvers is considered objectionable, it can be stopped entirely by an additional fixed seat provided in the frame for each louver blade as shown at 15 in Figs. 7 and 8. This seat is formed as a strip or ledge of any suitable material fixed to the side bars 11 and is preferably of a Babbitt metal which, by the use of appropriate forms can be poured directly in place when the louvers are fully closed and in the same manner as an ordinary Babbitt bearing, thereby producing a plurality of end seats, each accurately fitting its corresponding louver end and forming a close valve seating therefor. As shown in the drawings the pored valve seat 15 occupies an undercut groove in the side plate 12 whereby it is permanently and rigidly held in place.

From the foregoing description of the preferred form of the invention, it will be apparent that various modifications, additions, alterations and subtractions and changes in the form and shape and relative arrangement of the mechanism illustrated may be resorted to without departure from the principle of the invention as broadly set forth in the following claims.

Claims:

1. Pump valve mechanism comprising an organization of imbricated, pivoted louvers mutually cooperating as multiple valve members and end seats for the pivoted louvers.

2. Valve mechanism as in claim 1, the end seats being produced by pouring a Babbitt

metal into contact with the louvers when closed. 60

3. Valve mechanism as in claim 1, said end seats being formed with a ledge in interlocking engagement with the louver supports.

4. Pump valve mechanism comprising an organization of imbricated, pivoted louvers mutually cooperating as multiple valve members and back stops to limit the opening of the louvers to less than 90°. 65

5. Pump valve mechanism comprising an organization of imbricated, pivoted louvers mutually cooperating as multiple valve members, the series of louvers being disposed at an inclination providing for gravitational closing of each louver upon its 75 neighbor.

6. Pump valve mechanism comprising a plurality of adjacent valve frames conjointly controlling a single port passage and each frame carrying a plurality of imbricated valve louvers mutually cooperating as multiple valve members whereby each valve frame and its contained louvers may be affixed to and removed from the machine as 80 a unit. 85

7. The method of manufacturing valve elements which consists in producing a bar having a longitudinal thickening or bead along one side thereof cutting said bar into valve lengths and trimming the ends of 90 the beads to form pivots at each end of the valve element. 90

8. Pump valve mechanism comprising an organization of imbricated pivoted louvers cooperating as multiple valve members, a seat being provided for the lower edge of each louver and each louver comprising a blade portion and horizontal gudgeon pivots above the blade so that the closing of the 95 louvers is assisted by gravity. 100

9. A pump comprising a cylinder, a piston therein, and reversely-acting duplicate valve mechanisms for the inlet and outlet ports comprising valve frames containing imbricated pivoted louvers cooperating as multiple valve members. 105

10. A pump valve mechanism comprising a substantially planiform frame carrying a plurality of imbricated valve louvers cooperating as multiple valve members, said valve mechanism being reversible and thereby adapted for controlling both the suction and the discharge ports of the pump. 110

In testimony whereof, I have signed this specification.

ARTHUR S. HAWKS.
